CATTLE STANCHION

Filed Sept. 14, 1922

2 Sheets-Sheet 1

A technical drawing of a vertical assembly, possibly a door or panel, with the following components labeled:

- 14, 5: A top bracket or hinge assembly.
- 37: A vertical panel or frame on the left.
- 7: A vertical panel or frame on the left.
- 11: A vertical panel or frame on the left.
- 8: A vertical panel or frame in the center.
- 4: A vertical panel or frame on the right.
- 10: A vertical panel or frame on the right.
- 17: A bottom bracket or hinge assembly.
- 16: A vertical panel or frame on the right.
- 6, 15, 9: A bottom panel or frame at the bottom.

The drawing is labeled "Fig. 1" at the top.

UNITED STATES PATENT OFFICE.

JOSEPH A. STOCK, OF ENFIELD, MASSACHUSETTS, ASSIGNOR OF ONE-HALF TO EMORY H. BARTLETT, OF ENFIELD, MASSACHUSETTS.

CATTLE STANCHION.

Application filed September 14, 1922. Serial No. 588,249.

To all whom it may concern:

Be it known that I, JOSEPH A. STOCK, citizen of the United States, residing at Enfield, in the county of Hampshire and State 5 of Massachusetts, have invented new and useful Improvements in Cattle Stanchions, of which the following is a specification.

The present invention relates to cattle stanchions and has for its object to provide 10 certain new and useful improvements in the construction thereof.

The invention consists in the features of construction and in the novel combinations and arrangements of parts hereinafter described and particularly pointed out in the 15 appended claims.

In the accompanying drawings, illustrating the invention in its preferred form,—

Fig. 1 is a view, in side elevation, of the 20 improved stanchion;

Fig. 2 is a perspective view of the upper portion of the movable panel of the stanchion, the movable picket or fetter being shown in open position; and

Fig. 3 is a top plan view of the portion 25 of the movable panel shown in Fig. 2, the fetter being shown in closed position.

Referring first to Fig. 1 of the drawings, the movable panel 4 of the stanchion is pivotally mounted in the usual rigid and stationary frame comprising horizontal upper and lower beams or supports 5 and 6 and upright posts or pickets 7. The panel 4 comprises top and bottom crossbars 8 and 9, a fixed vertical picket 10 rigidly connecting the crossbars, and a movable picket or fetter 11 that is pivoted at its lower end to the bottom crossbar and is adapted to be swung in a vertical plane relatively to the picket 10 to open and close the stanchion. The crossbars 8 and 9 are severally centrally pivoted upon vertically alined pivot posts 14 and 15 projecting from the upper and lower stanchion supports 5 and 6, thereby enabling 40 the movable panel 4 to turn freely about a vertical axis as desired. The vertical picket 10 is rigidly secured, by means such as the cross pins 16, (Figs. 2 and 3) to the ends of the crossbars 8 and 9 at one side of the pivot posts 14 and 15. The movable picket or fetter 11 is pivoted at its lower extremity as indicated at 17, to the bottom crossbar 9 at the opposite end thereof from the picket 10. At the upper end of the

fetter 11 is carried a latch 18 by means of 55 which the fetter may be releasably secured in vertical or closed position. The latch 18 also serves to limit the swinging movement of the fetter away from the picket 10 and thus to determine the open position of the 60 fetter.

In accordance with the present invention, the latch 18 is made in the form of a yoke having flat side members 20 and a transverse member 21. The side members 20 of the 65 latch are preferably made of wood and are severally pivoted at one end by means of a rod 22 to the upper extremity of the fetter 11. The transverse member of the latch 18 consists of a metal rod which connects the 70 opposite or unpivoted ends of the wooden side members 20 and is adapted to slide along the upper surface of the top crossbar. The top crossbar 8 is provided with a deep longitudinal notch 24 which extends inwardly from one end thereof to receive the upper 75 end of the fetter 11 when the latter is in closed position. To maintain the fetter in registry with said notch so that it will readily enter the same, the fetter is held midway between the side members of the latch by means of spacing collars 25 on the pivot rod 22. To enable the fetter to be projected 80 into the notch 24 to the desired extent, the portions of the top cross bar at opposite 85 sides of said notch are also notched, as shown at 26, the notches 26 being horizontally alined to receive the spacing collars 25 as the fetter nears closed position. The latch rod 21 crosses the top crossbar 8 between the upper panel pivot 14 and the fixed picket end of said crossbar. The top crossbar 8 is notched, as shown clearly at 28 in Fig. 2 to receive the latch rod 21 when the fetter reaches closed position.

As the fetter approaches closed position, the latch rod 21 rides off from the upper surface of the top crossbar 8 and drops into the notch 28, a horizontal shoulder 29, which constitutes one side wall of the notch, limiting the downward movement of the latch and locating the latch pin in position for cooperative engagement with a vertical shoulder 30 which constitutes the other side wall of said notch. When the latch rod 21 is engaged with the shoulder 30 the latch is operative to securely hold the fetter 11 in closed position. The upper crossbar 8 is

further provided with horizontal ledges 32 which project from opposite sides thereof and underlie the side members 20 of the latch 18. These ledges 32 insure against the 5 possibility of the latch being lifted by the head or horns of the cow. Obviously the ledges 32 may also serve to limit the downward movement of the latch when the latch rod 21 rides off from the crossbar 8, thus 10 rendering it unnecessary to rely upon the shoulder 29 to perform this function.

When the stanchion is closed the fetter or movable picket is vertically disposed and is securely latched with its upper end seated 15 in the notch 24 of the top cross bar and with the pivot rod 22 extending through the slots 26 of said cross bar. Thus the movable picket and the top crossbar are firmly held against relative displacement so long as the 20 latch rod 21 remains in the notch 28.

To release the fetter 11 it is only necessary to raise the latch rod 21 above the shoulder 30 of the notch 28 whereupon the weight of the fetter will cause it to swing outwardly 25 away from the picket 10, drawing the latch rod 21 along the upper surface of the top crossbar until its movement is arrested by the panel pivot 14. To facilitate the raising of the latch yoke a pin or handle 34 may be 30 provided, as shown, at the outer side of one of the side members of the latch yoke. The side members of the latch yoke are extended somewhat beyond the pivot rod 22, as shown 35 at 35, at the opposite side from the latch rod 21 and these extensions are provided with bevelled under faces, which incline upwardly from the vertical plane of the pivot rod 22 to the free ends of the extensions 35, as shown at 36 in Fig. 2. This construction 40 permits the latch yoke to be conveniently raised from latched position by depressing one of the extensions 35. It will be noticed that the extensions 35 project beyond the fetter 11 and this construction enables them 45 to embrace a tongue or fin 37 (Fig. 1) on one of the upright frame members 7 when the stanchion is open and thus to hold the movable panel against turning so long as the stanchion remains open.

50 The above described stanchion is of simple and rugged construction and is particularly well adapted for its purpose for which it is intended. It may be either opened or closed with one hand and with the expenditure of 55 a minimum amount of effort. When closed, the stanchion cannot become accidentally unlatched. The entire structure, with the exception of the pivot rods, fastening bolts and the like is preferably constructed of wood 60 and the design of the stanchion is such that it is particularly economical to manufacture. The upper cross rod 8 and the side members 20 of the latch yoke may advantageously be

formed from a single block of wood substantially without waste of material. 65

The invention having been described what is claimed is:—

1. In a cattle stanchion, the combination with stationary upper and lower stanchion supports, of a movable panel comprising a 70 fixed vertical picket, a lower crossbar pivoted to said lower support and having one end rigidly secured to said picket, a fetter having its lower end pivoted to said crossbar, an upper crossbar pivoted to said upper support and having one end rigidly secured to the upper end of said picket and provided with a 75 latch face and having its opposite end free, a latch yoke having its side arms pivoted by means of a horizontal pintle to the top of 80 said fetter and having its cross arm engageable with and slidable along the upper face of the upper crossbar from the upper panel pivot to the fixed picket end thereof, the free end of said upper cross bar being longitudinally slotted in a vertical plane to receive 85 the upper end of the fetter when the latter is in closed position, the side arms of said latch yoke being spaced from the fetter to enable the upper cross bar projections at opposite sides of said slot to extend between 90 the fetter and the side arms of the latch yoke when the fetter is in closed position, and said upper cross bar projections being slotted longitudinally in horizontal planes to receive 95 said pintle when the fetter is in closed position.

2. In a cattle stanchion, the combination with stationary upper and lower stanchion supports, of a movable panel comprising a 100 lower cross bar pivoted to said lower support and a picket having its lower end rigidly fixed to one end of said cross bar, an upper cross bar pivoted to said upper support and having one end rigidly fixed to the upper 105 end of said picket and having a latch face at its end adjacent the said picket, a fetter pivoted at its lower end to the lower cross bar and having a pintle on its upper end, a latch member pivoted on the said pintle having side members that are spaced apart to 110 embrace the opposite side faces of said upper cross bar and provided with a transverse bar extending between the ends of said sides adapted to slidably engage the upper face of 115 the said upper cross bar and to engage the latch face thereof, the said upper cross bar being provided with intersecting slots at the end thereof for receiving the upper end of the pivoted fetter and the pintle between the outer faces of the fetter and the inner faces of the latch side members. 120

In testimony whereof I have affixed my signature.

JOSEPH A. STOCK.
